UNITED STATES PATENT OFFICE.

CHARLES B. ULRICH, OF JAMESTOWN, NEW YORK, ASSIGNOR TO ULRICH PLAN FILING & EQUIPMENT COMPANY, A COPARTNERSHIP FORMED OF CHARLES B. ULRICH AND ROY E. ULRICH, OF JAMESTOWN, NEW YORK.

FILING DEVICE.

Application filed March 25, 1926. Serial No. 97,283.

This invention relates to an improved filing device of the type which usually comprises a drawer, or similar receptacle, for containing a series of cards or the like, and which, in the form herein shown, is provided with a number of stub guides or dividers forming pockets to receive the lower edges of the cards, and to retain them in such a manner that any individual card or group of cards will be readily accessible and easily read.

The object of the present invention is to provide, in connection with the drawer or other receptacle for containing the cards, an improved false back or follower to be used for holding the cards in proper position when the receptacle is only partially filled. The invention also includes improved means for securing the false back within the drawer, so that it may be easily adjusted longitudinally thereof.

The specific construction of the invention and the advantages resulting therefrom will be more fully explained in the following detailed description, which is to be read in connection with the accompanying drawing illustrating one embodiment thereof.

In the drawing:

Figure 1 is a vertical longitudinal section of the invention.

Figure 2 is a perspective view of the removable bottom lining having stub guides secured thereto.

Figure 3 is a vertical transverse section taken on the line 3—3 of Figure 1.

Figure 4 is a perspective view of the false back.

The invention is illustrated in connection with a filing drawer, preferably constructed of metal, and having a bottom 5, sides 6 and ends 7. Each end is braced by an inside head 8 secured thereto, having a sloping face and provided at its lower edge with tongues 9, which extend through the bottom 5 and are locked thereto. A bottom lining 10, of suitable flexible material, is adapted to be inserted in the drawer, and is provided at each end with a tongue 11, which is adapted to extend through a slot 12 at the lower side of the sloping face. A number of stub guides 13 are connected to the bottom lining 10, each by two strips 14 of linen, paper or the like which are glued to the bottom lining 10 and stub guides 13, respec-

tively. These stub guides may be disposed in upright position, as shown in the left-hand portions of Figures 1 and 2, to receive cards between them, or they may be folded down flat against the bottom lining 10 when not in use, as shown in the right-hand portions of Figures 1 and 2.

When the drawer is only partially filled with cards, the length of the space containing them is limited by a false back 15, which is formed from a single piece of sheet metal, one edge of which is bent to form a forwardly extending horizontal base flange 16. At the upper edge of the false back, the metal composing the same is bent upon itself, as shown at 17, and extends downwardly, as indicated at 18, part way to the bottom, and is there bent rearwardly and then downwardly to form a rear base portion 19.

Each stub guide 13 is provided near each end with a hole 20, which also extends through the connecting strips 14 and, when the stub guide is lying flat on the bottom, registers with a hole 21 extending through the bottom lining 10. The edges of the holes 21 are preferably reinforced by metal eyelets. The rear base portion 19 of the false back is provided with a pair of tongues 22, which are adapted to be inserted in the corresponding holes 20 and 21. Thus, the false back 15 may be adjusted longitudinally so that any desired number of card pockets, defined by the stub guides 13, will be located in front of the same. The base portion 19 has substantially the same slope as the front face of the false back but slopes rearwardly, so that the rear portion of the drawer may be used for a separate file.

The portion 18 of the false back is bent to form a tubular bearing 23, extending from side to side of the drawer for receiving a pair of pins 24. Each side 6 of the drawer has its upper edge bent inwardly and downwardly, as at 25, and formed with a plurality of holes 26 which correspond in position to that of the pins 24, and are adapted to receive the same to secure the false back in any of its various positions of adjustment. Each pin 24 is provided with a projection 27, which serves as a handle and cooperates with a slot 28 in the tubular bearing 23 to secure the pin 24 either in projected or retracted position.

- It will be understood that the several stub guides 13 are provided to form pockets for receiving various groups of cards, and to retain the lower edges thereof, so that they 5 cannot slip downwardly underneath the other cards and become misplaced. The sloping faces of the inside heads 8, and the sloping faces of the false back 15 permit the cards to be tilted, so as to obtain ready access 10 to any desired card. The cards may be tilted without any lateral movement of their lower edges, and will stay in the position to which they have been tilted until they are positively moved. When there are 15 enough cards to fill only a portion of the drawer, the false back 15 may be readily adjusted to utilize any portion of the drawer desired.

While I have shown and described in detail one form in which the invention may be embodied, it is to be understood that various modifications may be made in the structure of the drawer, and in the arrangement of the various features without any material 20 departure from the spirit or scope of the invention as claimed.

What is claimed is:

1. In a filing device, a receptacle having a bottom with spaced transversely disposed stub guides flexibly connected thereto and formed with holes, and a false back having tongues engageable with the holes in any one of said stub guides when the latter lies flat on the bottom, thereby adjustably limiting the length of the space which receives the cards.
2. In a filing device, a receptacle having a bottom with spaced transversely disposed stub guides flexibly connected thereto and formed with holes, and a false back having a base with a forwardly extending flange adapted to lie flat on the bottom, and rearwardly extending tongues engageable with the holes in any one of the stub guides when the latter lies flat on the bottom, thereby adjustably limiting the length of the space between said false back and the front end of the receptacle.
3. In a filing device, a receptacle having a bottom with a removable lining, spaced transversely disposed stub guides flexibly connected to the lining and formed with holes, said bottom lining having holes registering with the holes in the respective guides when the latter lie flat thereon, and a false back having tongues engageable with the holes in any one of the guides and underneath said lining, thereby adjustably limiting the length of the space which receives the cards.
4. In a filing device, a receptacle having a bottom with a removable lining, spaced transversely disposed stub guides flexibly connected to the lining and formed with holes, said lining having holes registering with the holes in the respective guides when the latter lie flat thereon, the sides of the receptacle being formed with series of opposed holes, a false back having

with the holes in the respective guides when the latter lie flat thereon, and a false back having a base with a forwardly extending flange adapted to lie flat on the bottom lining, and rearwardly extending tongues engageable with the holes in any one of the guides and in said lining therebeneath, thereby adjustably limiting the position of the false back which forms the rear end of the space for receiving the cards.

5. In a filing device, a receptacle having a bottom with spaced transversely disposed stub guides flexibly connected thereto, the sides of the receptacle being formed with series of opposed holes, a false back having a base with forwardly and rearwardly projecting portions adapted to rest on the bottom, said false back being formed with a horizontal tubular bearing, and a pair of pins mounted in said bearing and projectable into corresponding opposed holes in the sides of the receptacle, thereby securing said false back so as to adjustably limit the length of the space which receives the cards.

6. In a filing device, a receptacle having a bottom with spaced transversely disposed stub guides flexibly connected thereto and formed with holes, the sides of the receptacle being formed with series of opposed holes, a false back having tongues engageable with the holes in any one of said stub guides when the latter lies flat on the bottom, said false back being formed with a horizontal tubular bearing, and a pair of pins mounted in said bearing and projectable into corresponding opposed holes in the sides of the receptacle, thereby supporting said false back so as to adjustably limit the length of the space which receives the cards.

7. In a filing device, a receptacle having a bottom with transversely disposed stub guides flexibly connected thereto and formed with holes, and a false back having a base with a forwardly extending flange adapted to lie flat on the bottom, and rearwardly extending tongues engageable with the holes in any one of said stub guides when the latter lies flat on the bottom, the sides of the receptacle being formed with series of opposed holes, said false back being formed with a horizontal tubular bearing, and a pair of pins mounted in said bearing and projectable into corresponding opposed holes in the sides of the receptacle, thereby securing said false back so as to adjustably limit the length of the space which receives the cards.

8. In a filing device, a receptacle having a bottom with a removable lining, spaced transversely disposed stub guides flexibly connected to the lining and formed with holes, said bottom lining having holes registering with the holes in the respective guides when the latter lie flat thereon, the sides of the receptacle being formed with series of opposed holes, a false back having

ing a base with forwardly and rearwardly projecting portions adapted to rest on the bottom, said false back having tongues engageable with the holes in any one of the 5 guides and in said lining therebeneath, said false back being also formed with a horizontal tubular bearing, and a pair of pins mounted in said bearing and projectable into corresponding opposed holes in the sides of 10 the receptacle, thereby securing said false back so as to adjustably limit the length of the space which receives the cards.

9. In a filing system, a receptacle having a bottom with a removable lining, spaced 14 transversely disposed stub guides flexibly connected to the lining and formed with holes, said bottom lining having holes registering with the holes in the respective guides when the latter lie flat thereon, a false back

having a base with a forwardly extending 20 flange adapted to lie flat on the bottom and having rearwardly extending tongues engageable with the holes in any one of said stub guides and in said lining therebeneath 25 when the stub guide lies flat on the bottom, the sides of the receptacle being formed with series of opposed holes, said false back being formed with a horizontal tubular bearing, and a pair of pins mounted in said bearing and projectable into corresponding opposed 30 holes in the sides of the receptacle, thereby securing said false back so as to adjustably limit the length of the space which receives the cards.

In testimony, that I claim the foregoing as 35 my own, I have hereto affixed my signature.

CHARLES B. ULRICH.
